ABSTRACT

Radiation-cleavable nondiffusible compounds for providing a transfer dye image are comprised of a spectral sensitizing dye moiety and a diffusible image dye moiety joined by a linkage in the spectral sensitizing dye moiety which is cleaved upon absorption of radiation by the spectral sensitizing dye moiety, thereby releasing a diffusible image dye. Such compounds are useful in radiation-sensitive elements and processes to provide dye images. Preferred compounds have the formula

where:

Q represents the atoms to complete a pyridine or quinoline ring;

SENS is attached to the 2 or 4 position of the pyridine or quinoline ring and represents the atoms which, in conjunction with N, complete a spectral sensitizing dye;

ALK represents an alkylene moiety of 1 to 8 carbon atoms;

DYE represents a diffusible photographic dye or dye precursor moiety; and

X⊖ represents an anion, if necessary to provide charge neutrality.
